UNITED STATES PATENT OFFICE.

PAUL GARRETT, OF NORFOLK, VIRGINIA.

DESIGN FOR A BOTTLE.

No. 39,215.

Specification for Design.

Patented March 24, 1908.

Application filed February 6, 1908. Serial No. 414,658. Term of patent 14 years.

To all whom it may concern:

Be it known that I, PAUL GARRETT, a citizen of the United States, residing at Norfolk, in the county of Norfolk and State of Virginia, have invented a new, original, and ornamental Design for Bottles, of which the following is a specification, reference being had to the accompanying drawing, forming part hereof.

In the drawing, the figure is a perspective view of a bottle, showing my new design.

I claim:—

The ornamental design for a bottle, as shown.

PAUL GARRETT.
